UNITED STATES PATENT OFFICE.

CLARE E. BEECH, OF MANSFIELD, OHIO, ASSIGNOR TO THE TAPPAN STOVE COMPANY,
OF MANSFIELD, OHIO, A CORPORATION OF OHIO.

RANGE.

Application filed October 15, 1924. Serial No. 743,679.

My invention relates to improvements in range structures, and more particularly to that type or class of gas ranges commonly known as "cabinet ranges."

The present improvements relate more specifically to the form and relation of the parts in the range body which is crated or shipped in a "knocked down" condition, the cooking top and burner box portions of the range being provided with removable cooking top, tray and drawer sections whereby when the latter are removed a vertical opening or clear space is formed within the outlines of the knocked down range body within which a man may step and walk in carrying, forming what may be termed a "one-man delivery" range.

A still further object is the provision of a burner box of the open bottom open front type, together with burner tray and drawer sections slidable in said burner box and removable from said open front, the drawer being adapted to normally form the bottom of the burner box in lieu of the ordinary burner box bottom and the tray normally closing the top of the drawer.

A still further object is the provision of a burner box with a drawer slidably mounted therein and insertible and removable through the open front of the burner box, together with means for limiting the opening and closing movements of the drawer and for permitting the latter to be inserted in and removed from the burner box by swinging horizontally to the stop side of the drawer with the stop as the swinging or pivot point.

With the above mentioned and other ends in view, the invention consists in the novel construction, arrangement and combination of parts, hereinafter described, illustrated in some of its embodiments in the accompanying drawings, and particularly pointed out in the appended claims.

Referring to the drawings, forming a part of this specification, Figure 1 is a perspective view of an ordinary gas range of the cabinet type, embodying improvements constructed and arranged in accordance with this invention, the sliding drawer being stopped in its open position preparatory to the initial removal of the drawer from or the initial insertion thereof in the burner box of the range.

Fig. 2, a top plan view of the range body

in knocked down condition for crating or transporting, the removable burner top tray and drawer sections being removed forming a vertical opening or clear space within the burner box into which a man may step and walk in carrying and balancing the knock down or crated range body as "a one-man delivery" range.

Fig. 3, a perspective view of the drawer section removed from the burner box of the range.

Fig. 4, an enlarged horizontal sectional view of the burner box portion of the range, showing the drawer withdrawn and stopped in its open position and illustrating in particular the manner in which the drawer is swung to one side using its stop as a pivot or swinging point in the initial insertion and removal of the drawer.

Fig. 5, a fragmentary front elevation of the burner box and one side of the burner tray and drawer, illustrating in particular the slide and stop features of the tray and drawer sections.

Fig. 6, a similar view in which the drawer is slidably mounted on a burner box bottom instead of being used in lieu of the latter and suspended from its top edges, as in Fig. 5 of the drawings.

Fig. 7 is a detail, partly in front elevation and partly in section, of a modification.

Similar numerals of reference designate like parts throughout all the figures of the drawings.

In the present instance, I have shown my improvements incorporated in a gas range of the conventional cabinet type, the cooking top, in this instance, being of the open type consisting of removable top grate sections 1, and the baker and broiler ovens 2 and 3, respectively, being on the right-hand side. The top has a shelf 10 at the left end. It will be apparent and should be understood that the improvements may be attached to or incorporated in range bodies of varying forms and types. The burner box is preferably of the open front type, as shown, and is preferably also open at its bottom so that when the removable top sections 1 and the usual burners and burner tray 4, and drawer section 5, are removed an opening or clear space A, will be formed within the outline of the range body into which a man may step when the range is in crated or knocked down position, as in Fig. 110.

2 of the drawings, forming what may be termed a "one-man delivery" range.

The sides 6 of the burner box are preferably provided with guide or glider members 6^a, for the burner tray 4, and where the bottom of the burner box is adapted to be formed by the bottom of the drawer section 5, the upper side margins of the drawer are preferably bent into laterally projecting side flanges 5^a, adapted to be slidably supported upon supplemental or drawer supporting glide members 6^b, as shown most clearly in Fig. 5 of the drawings. The guides or gliders 6^a and 6^b may be secured by means of suitable fastening elements 6^c. It will be seen that the members 6^a and 6^b constitute means for slidably and removably supporting the drawer and burner tray sections independently of each other, and that the burner tray 4 closes the top of the drawer when the latter is closed.

As a means of limiting the opening and closing movements of the drawer section 5, as well as permitting the latter to be inserted in and removed from the burner box by swinging the drawer section horizontally from its open stop position and to one side with the stop portion or member thereof as the swinging point, as indicated by dotted lines in Fig. 4 of the drawings, one side of the drawer,—in the present instance the side opposite the oven side of the burner box,—is provided with a stop member 5^b, adapted when the drawer is closed to come into engagement with the rear wall of the burner box (see Fig. 4) and when the drawer is pulled open to engage with the inturned flange 6^c at the front outer side of the burner box.

If desired, the sliding drawer may be used in a burner box having a burner box bottom 7, as illustrated in Fig. 6 of the drawings, and in which instance, the supplemental drawer supporting guide or glider members 6^b may be dispensed with, the drawer section in this case being slidably supported on the burner box bottom 7 through the medium of longitudinally extending ribs or runners 5^c.

In the form shown in Figs. 1 to 5, inclusive, of the drawings the top flange 5^a of the drawer slides directly beneath the burner tray glider 6^a and is thus kept horizontal and is prevented from tilting or dropping down when drawn out.

In Fig. 7 of the drawings I have shown a further modification in which the guide or glider members 6^a and 6^b for slidably

and removably supporting the drawer and burner tray sections are dispensed with and in which a horizontal partition 8 is mounted between the walls of the burner box and in which the horizontal wall or partition 8 forms a support for the burner tray 4 and a cover for the drawer section 5 when the latter is closed. In this instance, supplemental guide or glider members 6^e, similar to the drawer supporting glider members 6^b, are mounted to extend over the side drawer flanges 5^a so as to guide the drawer horizontally in its relative positions and particularly to prevent the drawer from tipping down at its outer end when it is partially open or withdrawn.

Having thus described some of the embodiments of my invention, without having attempted to set forth all the forms in which it may be made, or all the modes of its use, what I claim and desire to secure by Letters Patent is,—

1. A stove structure comprising a frame including a fixed burner box open at the top, bottom and front, a removable grate section at the top, a removable burner section under the grate section, and a removable drawer under the burner section, the removal of the grate, burner and drawer sections forming an opening from top to bottom thru the burner box, in which opening a man may stand to carry the stove.

2. A stove structure comprising a supporting frame having an oven at one side and an adjoining burner box at the other side, the burner box being open at the top, bottom and front, a removable grate in the top opening, a removable burner in the box under the grate, a removable burner pan in the box under the burner, and a removable drawer in the box, under the pan, whereby when the grate, burner, pan and drawer are removed the burner box forms an opening in which a man may stand to carry the stove.

3. A stove structure as set forth in claim 2, the sides of the burner box having guides on which the burner pan and drawer are slidable.

4. A stove structure as set forth in claim 2, the side wall of the burner box having a projecting flange, and the drawer box being slidable in and out the front opening and having a projection engageable with said flange to normally stop its withdrawal.

In testimony whereof I have affixed my signature.

CLARE E. BEECH.
